CLAIM

I claim the ornamental design for a spoon, as shown and described.

DESCRIPTION

FIG. 1 is a right side elevation view of the spoon, the left side elevation view being a mirror image.

FIG. 2 is a top plan view of the spoon.

FIG. 3 is a bottom plan view of the spoon; and,

FIG. 4 is a perspective view of the spoon.

The broken lines shown in the drawings are for illustrative purposes only and form no part of the claimed design.
